CLAIM

The ornamental design for a water meter, as shown and described.

DESCRIPTION

FIG. 1 is a perspective view showing the front, top and left side of a water meter which forms my new design, the broken lines in this and other figures indicating unclaimed environment and forming no part of the claim;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view there.
